UNITED STATES PATENT OFFICE.

LOUIS OSTERMEYER, OF PLEASANT HILL, MISSOURI.

CAR-FENDER.

No. 863,209.

Specification of Letters Patent.

Patented Aug. 13, 1907.

Application filed January 29, 1906. Serial No. 298,324.

To all whom it may concern:

Be it known that I, LOUIS OSTERMEYER, a citizen of the United States, residing at Pleasant Hill, in the county of Cass and State of Missouri, have invented 5 certain new and useful Improvements in Car-Fenders, of which the following is a specification.

My invention relates to car-fenders and its paramount object is to provide efficient means for preventing injury to any one who may be struck by a moving car. 10 Very many cases of severe injury are caused by the failure of the device to hold the person from rolling or being thrown from the fender even after they have been safely caught thereon. It has frequently happened that the person thus thrown off after having fallen upon 15 the fender has been run over by the car wheels and either severely maimed or killed, even when the first blow from the advanced edge of the fender has caused him no serious harm. In my improved apparatus I provide means for preventing such a result and also 20 take further precautions against injury by furnishing those portions of the apparatus, with which the body of the person struck may come in contact when falling upon the receiving surface, with soft covers or cushions of some suitable material. It is also noticeable that the 25 primary impact of the moving fender frequently causes bruises and broken bones; I prevent this result by placing upon the front of the fender a rubber cushion which may be made still more effective by constructing it in hollow form. 30 Further objects of my invention are, to provide means for reducing the size of the apparatus when not in actual use and for storing the same beneath the vestibule of the car where it will be out of the way.

I accomplish these and other objects in a general way 35 by constructing a rectangular framework capable of being folded upon itself and provided with removable sides and ends and having means for sliding the parts thus folded within a housing attached to the under side of the car.

40 In the drawings, Figure 1 is a side elevation of my improved fender and housing shown attached to the body of a car; Fig. 2 is a top plan view of the fender; Fig. 3 is a top plan view of the fender framework, the sides, rear piece and buffer having been removed; Fig. 45 4 is a side elevation of the fender framework in folded position and retracted within the housing one side of the latter being removed and a portion of a fender rail broken away; Fig. 5 is a front elevation of the fender complete; Fig. 6 is a cross section of Fig. 2, on the line 50 6-6, and Fig. 7 is a bottom plan view of one of the removable side pieces.

Referring to the drawings, A represents the body of a car beneath which and attached thereto is a rectangular housing B formed of side pieces b¹, provided 55 with longitudinal slots b² and connected by cross bars b³. The fender proper C is made in two parts, a rear

portion D and a front portion E, pivotally connected to each other by rivets c¹. The frame of the part D is composed of a bottom plate d¹ and side bars d² held together and rendered firmer by angle irons d³. From 60 the side bars d² project lugs d⁴ for engagement with the slots b². The frame of the front part E is likewise composed of a bottom plate e¹ and side bars e², strengthened by angle irons e³. In order to support the part E when extended, and to afford a certain degree of 65 resiliency to this portion a spring plate d⁵ is secured to the under side of the bottom plate d¹ projecting beneath the bottom plate e¹ but yielding sufficiently to allow the part E to be folded upon the rear part D. Projecting forward from the front part E are brackets 70 e⁴ which form a support for a buffer e⁵ removably secured by pins e⁶ and a bolt e⁷. This buffer may be covered with leather or otherwise padded or be constructed entirely of rubber, and made solid or hollow as desired. 75

In order to prevent any one who may be caught upon the fender from rolling or falling off again I provide the removable side boards F stiffened by angle irons f¹ and having internally projecting wings f² the under sides of which are formed with tenons f³, f⁴, 80 which interlock with the side pieces d², e², of the two portions of the framework of the fender. From the rear of each side board projects an angle iron f⁵ to support a removable rearboard G. Clips d⁶ secured to the side bars d² tend to hold the side boards more securely. 85

As a still further means of protection from injury I provide a yielding footboard H which is covered with some soft material and mounted upon springs h¹ which rest within holes e⁸ in the bottom plate e¹ and are supported by plates e⁹ secured to the under side of said plate e¹. 90

In order to prevent any one from getting under the wheels of the car fender-rails I are secured to the sides b¹ of the housing B and extend rearwardly substantially the whole length of the car. 95

When in use the two portions D and E of the fender C are drawn forward until the lugs d⁴ abut against the front end of the slots b² the side boards F and rear board G placed in position and the buffer e⁵ set over 100 the pins e⁶ and fastened in place by the bolt e⁷ the whole being held extended by the rod b⁴ which passes through holes in the side pieces b¹. When not in use the side and end boards and buffer are removed and the part E is folded back on the portion D. Then by 105 removing the locking rod b⁴ the structure thus folded can be retracted beneath the body of the car so that the said parts D and E are completely within the housing B and thus entirely out of the way. The removable parts F and G and e⁵, may be stored in any 110 convenient place within the car.

It is very evident that many changes may be made

in the devices of my invention without departing from the spirit thereof, and I do not, therefore, wish to be limited to the precise form and construction herein set forth, but

5 Having thus described my invention, what I claim as new, is:—

1. A car fender, including a housing attached to a car, a folding framework adapted to be retracted within the said housing, and side and end boards removably attached

10 to said framework.

2. A car fender, including a rectangular housing attached to a car, a folding framework adapted to be retracted within the housing, and removable side boards and ends for the framework.

15 3. A car fender, including a rectangular housing attached to a car, a folding framework adapted to be retracted within said housing, removable side boards and a removable buffer attached to said framework.

4. A car fender, including a rectangular housing attached to a car, a rectangular folding framework adapted when folded to be retracted within said housing, removable side and rear boards, a removable buffer and means for locking said framework in an extended position.

20 5. An apparatus for the purpose specified including a rectangular housing attached to the under side of a car, a rectangular framework capable of being folded upon itself and retracted within the said housing, removable side and rear boards, a removable buffer, means for supporting the said rectangular framework in an extended position, and

25 means for locking the framework in said extended position.

6. An apparatus for the purpose specified including a rectangular housing attached to the under side of a car, a rectangular framework capable of being folded upon itself and retracted within the said housing, removable side and

30 rear boards, a removable buffer, means for supporting the said rectangular framework in an extended position, and means for locking the framework in its extended position.

7. An apparatus for the purpose specified including a rectangular housing attached to the under side of a car, a rectangular framework capable of being folded upon itself and retracted within the said housing, removable side and rear boards, means for supporting said rectangular framework in an extended position, means for locking said framework in such position, a removable buffer and a yielding foot plate.

40 8. An apparatus for the purpose specified including a rectangular housing attached to the under side of a car, a rectangular framework capable of being folded upon itself and retracted within said housing, a removable buffer, means for supporting the said rectangular framework in an extended position, means for locking the framework in said position, a yielding foot plate, removable side boards, and fending rails for preventing persons from falling beneath the car wheels.

45 9. An apparatus for the purpose specified including a rectangular housing attached to the under side of a car, a rectangular framework capable of being folded upon itself and retracted within said housing, a removable buffer, means for supporting said rectangular framework in an extended position, means for locking the framework in said position, a yielding foot plate, removable side and rear boards and fending rails extending rearwardly from the said housing along the sides of said car substantially the length of the car.

50 In testimony whereof I affix my signature in presence of two witnesses.

LOUIS OSTERMEYER.
